WATER WHEEL UNIT

Original Filed Feb. 26, 1924 2 Sheets-Sheet 2

INVENTOR.

FRANK L. McQUISTON

BY *Munn & Co.*
ATTORNEYS.

UNITED STATES PATENT OFFICE.

FRANK L. MCQUISTON, OF REDONDO BEACH, CALIFORNIA.

WATER-WHEEL UNIT.

Original application filed February 26, 1924, Serial No. 695,334. Divided and this application filed September 22, 1925. Serial No. 57,922.

My invention relates generally to water motors and particularly to water wheels therefor, and is a division of my co-pending application Serial Number 695,334 filed 5 February 26, 1924.

It is a purpose of my present invention to provide a water wheel unit embodying a plurality of wheels mounted for bodily oscillating movement and rotational movement 10 about their own axes, each wheel having blades automatically feathered under the action of the moving water in which they are submerged to fully utilize the power of the moving water in effecting rotation there- 15 of.

I will describe only one form of water wheel unit embodying my invention, and will then point out the novel features thereof in claims.

20 In the accompanying drawings,

Figure 1 is a view showing in side elevation one form of water wheel unit embodying my invention in applied position within a water motor;

25 Figure 2 is a vertical sectional view taken on the line 2-2 of Figure 1;

Figure 3 is an enlarged vertical and longitudinal sectional view of the water wheel unit shown in the preceding views.

30 Referring specifically to the drawings, in which similar reference characters refer to similar parts in each of the views, my invention in its present embodiment is shown associated with a stationary frame made up of vertical beams 15 and 16 and horizontal beams 18, the frame being of rectangular form and with the vertical beams adapted to be imbedded in the bottom of the body of water in which it is adapted to operate. A 35 sector gear S is suitably secured to the frame, and this gear is made up of an annulus 19 provided with flanges 20 in which are secured rods 20^a constituting teeth.

40 A carriage, designated generally at K, is supported for swinging movement upon the frame by means of stationary hangers 21 and 21^a secured to and depending from the horizontal beams 18 and receiving shafts 22 and 22^a. Movable hangers 23 and 23^a are 45 mounted on the shafts 22 and are provided with bearings 24 and 24^a which receive shafts 25 and 25^a. The shafts are journaled in bearings 26 and 26^a secured to the carriage K.

By this arrangement the hangers 23 and 55 23^a are pivotally sustained upon the stationary hangers 21 and 21^a, and the latter through the shafts 25 and 25^a serve to support the carriage K for pivotal movement about the shafts 22 and 22^a as a center. 60

Suitably journaled in the beams 18 of the frame is a shaft 27 which constitutes the driven member of the motor from which power is adapted to be taken for performing useful work. This shaft is adapted to be 65 continuously rotated in the same direction, and in the present instance I have shown a single water wheel unit embodying my invention operatively connected to the shaft 27 for driving the latter, but as this connection forms no part of the present invention, a detail description thereof is omitted. 70

The water wheel unit embodying my invention comprises an upper water wheel W, an intermediate water wheel W' and a 75 lower wheel W². As clearly shown in Figures 1 and 2, these three wheels are arranged at different levels upon the carriage K and are wholly supported by the carriage K so as to move with the latter. As shown 80 in Figure 3, the wheel W comprises a cylindrical body 28, the ends of which are secured to flanged disks 29. Stub shafts 30 are fixed to the disks 29 and are journaled in bearings 31 formed on brackets 32 secured to the carriage K. Blades 33 are pivoted at the points indicated at 34 to the disks 29 so as to be free to occupy active or inactive positions with respect to a body of moving water or what is commonly known as feathering. 90 Subsidiary blades 35 are pivoted to the disks 29 at the points indicated at 40, and these blades are adapted to be engaged by the blades 33, whereby the latter are sustained for the proper interval in active position 95 so as to oppose movement of the water and thus set up rotation of the wheel as a unit. In the active position of the blades 33 they engage the lower edge of one blade 33 and the inner face of an adjacent blade 33, thereby holding the two blades against movement to a horizontal position in order that the force of the moving water may act upon the blades and thus set up rotation of the wheel. However, as the wheel rotates the movement 100 of the water upon the opposite sides of the blade 33 allows them to swing free of the subsidiary blades 35 so that their edges are 105

presented to the moving water and thus occupying what I have termed as the inactive position.

The wheels W' and W^2 are identical in construction so that a description of one will suffice for both. The wheel W' comprises a cylindrical body 41, to the ends of which are secured flanged disks 42, and the shafts 25 and 25^a are journaled in bearings 43 carried by the disks 42. Blades 44, preferably of concave form, are mounted upon the body to occupy active or inactive positions, and curved deflecting plates 45 are pivoted to the blades at the points 46 for directing moving water against the outer marginal edges of the blades 44 so as to secure the greatest possible leverage, as will be understood. These blades 44 are connected in pairs by arms 47 and 48 secured to the blades of any one pair and pivotally connected to each other by means of a link 49. The arms 48 are fixedly secured to the inner edges of the blades 44 and extend into the body 41 through openings 50, their inner ends being operatively connected to each other through the link 49. The association of the arms and link is such that when one blade 44 is in active position, the corresponding blade 44 is in inactive position, and when the active blade is moved to inactive position the inactive blade is moved to active position. In the active position of either blade it is disposed radially with respect to the body 41 of the deflecting plate 45 occupying what may be termed a tangential position with respect to the body 41 so that water impinging thereagainst will be directed to the marginal edge of the blade 44. In the inactive position of either blade 44 it is folded against the body 41 so as to offer the least possible resistance to the movement of the water, the deflecting plate being also folded and interposed between the blade 44 and the body. A water wheel constructed in this manner is practically indestructible and cannot be damaged by rocks or other solid matter traversing a body of water in which the motor is operating because the body 41 is rounded and will therefore deflect solid matter to either side of the body, while the blades when in inactive position are folded up against the cylindrical body and, being of approximately the same curvature, will function in the same manner with respect to solid matter as the body. Furthermore, the blades, when in active position, are free to move with the wheel so as to respond to any moving solid matter.

As previously described, the water wheels of the unit are mounted upon the carriage K and are thus capable of bodily movement in addition to being rotatable about their own axes. As the carriage K is free to swing, it will be clear that under the action of a moving body of water, the wheels, in addition to being rotated, will also serve to swing the carriage in the direction of movement of the body of water, and this movement is utilized by the mechanism shown and described in detail in the co-pending application hereinbefore referred to. Similarly, the mechanism for transmitting rotary motion from the wheels W , W' and W^2 to the shaft 22 is shown, but described in detail in the co-pending application.

Although I have herein shown and described only one form of water wheel unit embodying my invention, it is to be understood that various changes and modifications may be made herein without departing from the spirit of the invention and the spirit and scope of the appended claims.

What I claim is:

1. A water wheel comprising a curved body mounted for rotational movement, blades movable on the body to occupy active and inactive positions, and arms rigidly connected to the blades and extending into and rocking on the body connecting the blades in pairs whereby the movement of one blade of a pair from active to inactive position will move the other blade from inactive to active position.

2. A water wheel comprising a cylindrical body mounted for rotational movement, blades mounted to occupy active and inactive positions to permit feathering thereof, and arms rigidly connected to the blades and extending into and rocking on the body and connecting the blades in pairs whereby the movement of one blade of a pair from active to inactive position will move the blade from inactive to active position.

3. A water wheel comprising a cylindrical body mounted for rotational movement, blades mounted to occupy active and inactive positions to permit feathering thereof, arms rigidly connected to the blades and extending into and rocking on the body, a link connecting the arms, the said arms connecting the blades in pairs, whereby the movement of one blade of a pair from active to inactive position will serve to move the blade from inactive to active position.

FRANK L. McQUISTON.
